Primary Examiner — Rosemary K Tarcza(74) *Attorney, Agent, or Firm* — Leading Edge Law Group, PLC**CLAIM**

The ornamental design for a vehicle battery recharging station, as shown and described.

DESCRIPTION

FIG. 1 is a front perspective view of the vehicle battery recharging station illustrating our design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top elevation view thereof; and,

FIG. 7 is a bottom elevation view thereof.

The broken lines in the drawings are for the purpose of illustrating the unclaimed portions of the vehicle battery recharging station and form no part of the claimed design.
